[57] CLAIM

The ornamental design for support bracket for a household appliance such as a hair dryer, as shown and described.

DESCRIPTION

FIG. 1 is a perspective view of support bracket for a household appliance such as a hair dryer embodying my new design;

FIG. 2 is a plan view thereof;

FIG. 3 is a side elevational view thereof;

FIG. 4 is a bottom view thereof;

FIG. 5 is a rear elevational view thereof; and,

FIG. 6 is a front elevational view thereof.

The undisclosed left side is a mirror image of the right side shown in FIG. 3.

FIG. 1

FIG. 2

FIG. 5

FIG. 6

FIG. 3

FIG. 4
